(57) **CLAIM**

The ornamental design for a unibody dual mop bucket, as shown and described.

DESCRIPTION

FIG. 1 is a top perspective view of a unibody dual mop bucket showing our new design;

FIG. 2 is a first end view thereof;

FIG. 3 is a second end view thereof;

FIG. 4 is a first side view thereof, the opposite side being identical thereto;

FIG. 5 is a top plan view thereof;

FIG. 6 is a top perspective view thereof; and,

FIG. 7 is a first side view thereof.

The broken lines shown in all the views are for illustrative purposes only and form no part of the claimed design.
